UNITED STATES PATENT OFFICE.

CHARLES W. HART, OF TROY, NEW YORK, ASSIGNOR TO MYRTIE E. BUTTON,
OF SAME PLACE.

DESIGN FOR A FULCRUM-POST.

SPECIFICATION forming part of Design No. 29,898, dated December 27, 1898.

Application filed November 30, 1898. Serial No. 607,921. Term of patent 14 years.

To all whom it may concern:

Be it known that I, CHARLES W. HART, a citizen of the United States, residing at the city of Troy, county of Rensselaer, and State of New York, have invented and produced a new and original Design for a Fulcrum-Post, of which the following is a description, reference being had to the accompanying drawings.

- 10 Figure 1 is a top plan view of a fulcrum-post embodying my design. Fig. 2 is a bottom plan view of the same. Fig. 3 is a side view of the same. Fig. 4 is an edge view of the same.
- 15 The post comprises the body A, having an eye A', and the depending legs B B, which extend outwardly and downwardly in curved lines from the body and then downwardly, with their inner surfaces approximately par-
- 20 allel, the horizontally-projecting wings C C, and the spurs D D.

The wings C C project oppositely from the body part near the junction of the legs therewith and give to the post the general form of a cross when viewed either from the top, bottom, or edge, as shown in Figs. 1, 2, and 4.

25 The spurs D D are wedge-shaped and are arranged diagonally opposite each other on the under side of the body part and wings C C.

The leading feature of the design consists 30 of the post having the general form of a cross when viewed from the top, bottom, or edge.

What I claim as new, and desire to secure by Letters Patent, is—

35 The design for a fulcrum-post herein shown and described.

In testimony whereof I have hereunto set my hand this 29th day of November, 1898.

CHARLES W. HART.
